WINDOW

Albert Kaspar, Cicero, Ill.

Application October 25, 1932, Serial No. 639,397

2 Claims. (Cl. 189—66)

This invention relates generally to improvements in windows and has particular reference to windows having stationary or slidable sashes and glass-carrying frames mounted in such sashes.

One of the objects of this invention resides in the provision of a window in which the glass-carrying frame may be tilted inwardly within the sashes for the purpose of cleaning or washing of the outside surface of the glass as well as the inside surface, from the interior of the building. The glass frame may be tilted to a horizontal position for cleaning, or may be tilted inwardly into an angular position for ventilating purposes. Another object of the invention is to provide the glass frame with a pair of pivotally mounted arms which will balance the glass frame at any desirable angular position. Another object is to provide means for preventing the glass frame from tilting or moving out of its angular position by air pressure or strong winds, which consists in providing the top rail of the glass frame with a hook which swings outwardly and may be hooked to an eye screw fastened to the top rail of the sash. By this hook the glass frame may be securely held in angular ventilating position. The glass frame being tilted from the top rail for ventilating does not cause an opening at bottom of glass frame and thus insures perfect ventilation in such tilted position.

This invention it will be understood is applicable to one or more sashes in one frame. In slidable or double hung window sashes, the bottom sash may be raised to the extreme position and the top sash may be lowered to the sill. The top sash glass frame may be tilted inward for convenience of washing or cleaning the outer surface of the glass without the use of a chair or ladder. The glass frame tilting entirely inwardly eliminates the removal of screens, storm windows, or any attachments such as may be mounted on the outside of the sash or frame. A further and important object resides in the provision of a simple sash and glass frame including durable and inexpensive construction embodying simple interlocking weatherstripping of the rubber or felt which insures the mounting of the glass frame in the sash absolutely weatherproof. The glass frame may be constructed in drawn (or art) metal or wood molding. A still further object of the invention is the improved construction which permits the glass frame, when closed, to lie entirely within the sash, leaving only a slight parting line between the glass frame and sash which is almost unnoticeable and has

the appearance of the regular one piece molding and sash. It shall be understood that this type of glass frame may be applied to the present types of metal or wooden windows.

With the above and other objects in view, my invention consists in the novel combination, construction and arrangement of the parts and members shown in preferred embodiment in the attached drawings, described in the following specifications and particularly pointed out in the appended claims.

Referring to the drawings:

Fig. 1 is a vertical sectional view of a slidable sash window embodying the invention.

Fig. 2 is a transverse section of the same, the line of section being at 2—2 of Fig. 1.

Fig. 3 is a vertical sectional view of a window embodying the invention, with the sash being of wood.

Fig. 4 is a transverse section of the same on the line 4—4 of Fig. 3.

Fig. 5 is an enlarged sectional detail, showing the upper sash top rail and the top rail of the glass frame of the form of construction shown in Fig. 1.

Fig. 6 is an enlarged sectional detail, showing the lower sash bottom rail and the bottom rail of the lower glass frame.

In the illustrations shown in Figs. 1 to 5, inclusive, the upper sash is indicated by 20 and the lower sash by 21.

The window frame 22 is fabricated of sheet metal to form the top 22^A, sill 22^B and sides 22^C which form the balance weight boxes.

The upper and lower sash are formed substantially of a frame consisting of a channel member 23.

The top 22^A of the frame is formed to support a sash seat 24 formed of channeled cross-section and secured by screws 25. When the upper sash 20 is raised to its uppermost position, the top channel rail 23 embraces the seat 24.

Secured to the sill 22^B by screws 25 is a lower sash seat 26 which is adapted to be embraced within the bottom channel rail 23 of the lower sash 21.

The bottom rail 23 of the upper sash 20 and the top rail 23 of the lower sash 21 are covered with metal plate covers 27 which are secured to the rails by screws 28. The covers 27 are formed with integral extensions 27^A arranged to interlock with each other to form a weatherproof seal between the upper and lower sash. It will be observed that the extensions 27^A are formed to provide recesses for rubber or felt gaskets 29 into

which ends 27^A are projected to form an interlocking weatherproof seal.

Guides 30 are screwed or otherwise secured to the sides 22^C to provide vertical guiding means 5 for the upper and lower sashes. The guides 30 are of sheet metal and comprise a side 30^A with a longitudinally right-angularly extending end 30^B. Near the end 30^B, the side wall 30^A is bent outwardly to form a guideway 30^C for one flange of 10 the side rails of the sash. The free edge of the side 30^A of the guide 30 is spaced from the corner of the side 22^C to form as at 30^D a guideway for the other flange of the upper sash side rail 23, and the free edge of the side 30^A of the co-operating adjacent guide 30 is spaced from end 30^B 15 of the guide 30 for the upper sash to form as at 30^E a guideway for the other flange of the lower sash side rail 23.

On the inner face of one flange of each channel 20 side rail 23, I weld, or otherwise secure, a suitable hook 31 to which the balance weight chain 32 is secured and which chain is trained over the pulley 33 mounted on the style of the weight box 22^C.

The glass-carrying frames or tiltable glass 25 frames 34 are fabricated of metal which is mitred and welded at the corners. A backing 35 of L-shaped cross-section, is spotwelded, or otherwise secured, to the top and side members of the glass frame along the edges 34^A. The bottom 30 members of the glass frames are closed by a backing 36 which is also spot-welded, or otherwise secured, thereto and which is formed with a longitudinally extending recess 36^A for the rubber or 35 felt gasket 37. The moulding 34 is formed with a shoulder or seat 34^B of L-shaped cross-section to receive the glass 38 which is retained in place by a stop 39 of L-shaped cross-section.

The moulding 34 may be provided with a reinforcing bar 34^C secured on the inner face of one 40 edge of the glass seat 34^B to increase the cross-section of the metal along such portion to insure a substantial support for the screws 40 which retain the glass stop 39.

The top and side channel rails 23 of the sash 45 are provided with a metal weatherstrip 41 of L-shaped cross-section secured thereto by screws 42 which weatherstrips 41 retain gaskets 43 of rubber or felt which are engaged by the edges of the moulding 34 and 35 to thus form a weather- 50 proof seal therewith.

The bottom rails 23 of the sash are provided with a metal weatherstrip 44 of Z-shaped cross-section secured thereto by screws 45, which weatherstrips 44 are adapted to engage the gaskets 37 to thereby form a weatherproof seal therewith.

The lower corners of the glass frames 34 are provided with guide studs or pins 47 which are mounted in the re-enforcing angles 48. The 55 guide pins 47 are confined to a vertically extending path of movement within the slots 49 formed within the side sash rails 23.

The adaptation of the invention to window sash of wood construction will be quite obvious from 60 the above description, but in order to render such application clear, the use of the invention with wood sash is illustrated more particularly in Figs. 3 and 4, which will now be described in detail.

The weatherproofing of the top and side rails of the glass frames 60 consists of a weatherstrip or metal plate 61 set into a recess 60^A and having a free edge 61^A projecting over a second recess 60^B. The sash 62 is provided with a weatherstrip or metal plate 63 of L cross section extending along the top and side rails thereof and having an inwardly bent leg or flange 63^A positioned in spaced relation to the inner face of the sash rail to support therebetween a gasket 64 of rubber or felt which gasket is adapted to be engaged by the free end 63^A of the plate 63 to thus weather-seal the top and sides of the glass frame 60.

The bottom rails of the glass frame 60 are provided with a recess 60^C and a second recess 60^D formed within the recess 60^C. These recesses 60^C and 60^D are preferably lined with a metal plate 65. The recess 60^D is adapted to retain a gasket 66. The bottom rail of the sash 62 is provided with a weatherstrip or metal plate 67 of L cross-section having one vertical leg 67^A secured to the outer face of the sash 62 and the other vertical leg 67^B disposed to project into the recess 60^D into engagement with the gasket 66 to thus provide a weather-seal between the bottom of the glass frame and the sash.

The lower end of each glass frame is provided with a pair of guide pins 47 which are confined to vertical movement in guides 68 which consist of a vertically disposed plate bent to form an inverted elongated U and set within elongated slots or recesses 62^A, on the inner faces of the side rails of the sash 62. The plate guides 68 are formed with integral teeth 68^A to engage within the sash and thus retain the guides in place.

I claim:

1. A window including a vertical movable sash, a relatively swinging frame mounted within and movable with the sash, a sealing element for the frame carried by the sash on the side and upper 40 rails of the latter, means integral with the frame for cooperating with said sealing elements when the frame is in closed relation to the sash, sealing means for the lower end of the frame and carried thereby, an element on the sash for cooperating 45 with the latter sealing means when the frame is in closed relation to the sash, the cooperation of the element and sealing means permitting limited swinging movement of the frame without interfering with the seal.

2. A window including a vertical movable sash, a relatively swinging frame mounted within and movable with the sash, an angular flange secured to the side and top rails of the sash, a sealing gasket carried by said flanges, means integral 55 with the sides and top of the frame for directly engaging the gaskets as the frame is moved to closed relation with the sash, the lower rail of the frame being formed near one edge with a channel open at the bottom and closed at the top, 60 a gasket secured within said channel, and an element carried by the sash to project into said channel and engage the gasket therein when the frame is in closed relation to the sash, the width of the channel relative to that of the element permitting 65 a limited swinging movement of the frame relative to the sash without interfering with the sealing cooperation.

ALBERT KASPAR.
